UNITED STATES PATENT OFFICE.

FREDERICK A. GREARSON, OF BARRE, VERMONT, ASSIGNOR TO GREARSON & LANE COMPANY, OF BARRE, VERMONT, A CORPORATION OF VERMONT.

DESIGN FOR A MONUMENT.

54,911.

Specification for Design.

Patented Apr. 20, 1920.

Application filed January 16, 1919. Serial No. 271,529. Term of patent 14 years.

To all whom it may concern:

Be it known that I, FREDERICK A. GREARSON, a citizen of the United States, residing at Barre, in the county of Washington and State of Vermont, have invented a new, original, and ornamental Design for Monuments, of which the following is a specification, reference being had to the accompanying drawing, forming a part thereof.

Figure 1 is a perspective view of a monument, showing my new design; and

Fig. 2, a perspective view taken from a point to disclose the rear of the monument.

I claim:

The ornamental design for a monument, as shown.

FREDERICK A. GREARSON.
